UNITED STATES PATENT OFFICE.

E. LOUIS LOWE, JR., OF BROOKLYN, NEW YORK.

MACHINE FOR OBTAINING FIBERS FROM FIBER-BEARING SUBSTANCES.

SPECIFICATION forming part of Letters Patent No. 292,240, dated January 22, 1884.

Application filed November 17, 1883. (No model.)

To all whom it may concern:

Be it known that I, E. LOUIS LOWE, Jr., of the city of Brooklyn, in the county of Kings and State of New York, have invented a new and useful Improvement in Machines for Obtaining Fibers from Fiber-Bearing Substances, of which the following is a specification.

My invention relates to machines for obtaining fibers, in which are combined a bed or concave and a rotary cylinder arranged above and in the bed or concave; and it consists in various novel features in the construction of many of the parts of such machines, and in the manner of combining the parts together, all as hereinafter described, and as set forth in the claims.

In the accompanying drawings, Figure 1 is a side elevation of a machine embodying my invention. Fig. 2 is a vertical section in a plane transverse to the axis of the cylinder and just within one of the side frames of the machine, and Fig. 3 is a plan of the machine.

Similar letters of reference designate corresponding parts in all the figures.

The principal working parts or members of the machine are a bed or concave, A, of approximately semicircular shape, and a cylinder, which is of approximately circular shape, although it may vary somewhat from a true cylinder. The bed or concave A, here shown, is composed of a main or principal portion, which extends beneath the cylinder and upward on the delivery side of the machine, and which is fixed in position, and an adjustable portion or section, A', which is at the entrance side of the machine. By "entrance side" I mean that side on which the plants or other materials to be operated on are introduced, and by "delivery side" I mean that side on which the plants or materials leave the machine after being operated upon.

B designates the side frames of the machine. They are provided on their inner sides with segmental flanges or ribs a, to which the staves b, which form the fixed portion of the bed or concave, are secured by bolts c. The staves b', which form the adjustable portion A' of the concave, are secured to curved supports a', which are hinged at a' to the side frames, B. The said adjustable portion A' is held in place by screws d, which fit in nuts d', secured to

the side frames, B, and by adjusting these screws the adjustable section A' may be moved or swung to vary the distance between it and the cylinder, and this without moving the main or principal portion of the bed or concave. The cylinder comprises a shaft, C, heads or circular supports C', secured on the shaft, and staves e, which are secured to the flanges e' of the heads or supports C' by bolts e', and which form the working-surface of the cylinder.

The staves b b' of the bed or concave and the staves e of the cylinder are shown as provided on opposite sides or faces with grooves, and are reversible, so that either side or face may be presented outward for use. They may be unbolted from their heads or supports C, reversed in position, and again secured in place. As shown, the grooves in what are now their inner sides or faces are of finer pitch than the grooves in what are now their outer sides or faces, and this construction may render them better adapted for operating upon different materials. Even if the grooves or projections on both sides were of like pitch, the staves would be susceptible of longer use, for when one side became smooth they could be reversed in position.

In the cylinder are pockets or cavities C², of which there may be one or more, two being shown. A description of one will apply to both.

In the peripheries of the heads or supports C' are depressions or recesses f, and in these is seated or arranged an adjustable section of stave, C³, which may be of metal. As shown, it is provided with lugs or ears f', and is hinged to the heads or supports C' by a bolt passing through these lugs or ears and the heads or supports. It may have a smooth surface, or its surface may be grooved or roughened.

At each end of the stave or section C³ is a bolt or screw, f², having a nut, f³, which is fitted and held against movement lengthwise of the screw in a recess in the flange e' of the head or support C'. As shown, the nut is concave lengthwise of the screw, and the walls of the recess which holds it are convex; hence the nut is not only capable of turning, but may swing slightly in its recesses, to accommodate itself to the varying angles at which the

screw will extend as the stave or section C³ is moved inward and outward by turning the nut. By moving the section C³ in or out relatively to the center of the cylinder the size of the pocket or cavity C² is increased or diminished in size. The pocket or cavity C² greatly facilitates the introduction of material into the machine, as it affords an increased space between the cylinder and concave when the said pocket or cavity comes to the entrance side of the machine.

D designates the boxes or bearings for the cylinder-shaft C. They rest on the side frames, B, and are each provided with lateral extensions D' and a downwardly-extending arm, D², in which is a slot, g.

Through the extensions D' extend bolts g', which pass through slots g² in the side frame, B, as shown dotted in Figs. 1 and 3, and have springs g³ applied to them above the boxes. These springs hold the cylinder down with a yielding force, but still permit it to rise. Setscrews g⁴, inserted through the extensions D' and impinging on the top of the side frame, B, limit the downward movement of the box and cylinder.

Through the slotted arms D² are inserted bolts g⁵, which guide the boxes in rising and falling, and the lower one of which limits the rising movement by reason of the lower end of the slot g coming against it. The two bolts g⁵ aid in steadyng the box and preventing its eanting when it is raised off its seat on the side frame, B.

35 For operating upon different materials it is desirable to vary the distance between the cylinder and bed or concave at the entrance and delivery sides of the machine, and this is effected by shifting the boxes D horizontally.

40 In the side frames, B, are three sets of holes, g⁶, for the bolts g⁵, thus providing for different degrees of adjustment of the cylinder. These holes are shown in Fig. 1, the bolts g⁵ being screwed into one set.

45 Upon the shaft C of the cylinder is a spur-wheel, E, which receives motion from a second wheel, F, on a shaft, F', and the shaft F' receives motion from a wheel, G, secured upon a driving-shaft, G', and gearing with the wheel 50 F.

55 On the shaft G' is a pulley, G², for a driving-belt. Obviously the shaft G' and wheel G might be dispensed with, and the pulley G² placed on the shaft F', but the motion imparted to the cylinder would not be so slow as it now is. When the cylinder is shifted horizontally, the shaft F' must also be shifted to maintain the wheels E F in gear. In this example of my invention I provide for this by 60 mounting the shaft F' in eccentric-boxes, h, which are fitted and adapted to turn in seats or holes h' in the side frames, B. Each box has a flange, h², and is secured against accidental turning by a bolt, i, inserted through 65 the flange and entering the side frame. By turning the boxes h a quarter of a turn, the

shaft F' and the cylinder may be shifted, so that the bolts g⁵ will enter the middle set of holes, g⁶, and the boxes are then secured by inserting the bolts i in either of two holes, i' i', 70 in the side frames. By turning the boxes half a turn, the shaft F' and cylinder may be shifted, so that the bolts g⁵ will enter the set of holes g⁶, farthest to the left in Fig. 1, and the boxes h are then secured by inserting the bolts i in holes i² in the side frames, B. The shaft G' 75 is also mounted in eccentric-boxes h, like those above described, secured in a like manner in different positions.

What I claim as my invention, and desire to 80 secure by Letters Patent, is—

1. In a machine for obtaining fibers, a rotary cylinder composed of heads or supports and reversible staves secured to said heads or supports, and having opposite sides or faces 85 grooved or roughened, so that either side or face may be presented for use, substantially as described.

2. In a machine for obtaining fibers, a bed or concave composed of supports and reversible staves secured to said supports, and having opposite sides or faces grooved or roughened, so that either side or face may be presented for use, substantially as described. 90

3. In a machine for obtaining fibers, a rotary cylinder composed of heads or supports and reversible staves secured to said heads or supports, and having in their opposite sides grooves or projections of different pitch, whereby provision is afforded, by reversing the 95 staves, for operating upon different materials more effectively, substantially as described. 100

4. In a machine for obtaining fibers, a bed or concave composed of supports and reversible staves secured to said supports, and having 105 in their opposite sides grooves or projections of different pitch, whereby provision is afforded, by reversing the staves, for operating upon different materials more effectively, substantially as described. 110

5. In a machine for obtaining fibers, the combination of a rotary cylinder and a bed or concave, both having their working-surfaces composed of reversible staves, which are grooved or roughened on opposite sides or faces, so that 115 either side may be presented for use, substantially as described.

6. In a machine for obtaining fibers, the combination, with a bed or concave, of a rotary cylinder consisting of heads or circular supports having formed in their peripheries depressions or recesses, and staves secured to said heads or supports, a movable section or stave arranged in the depressions or recesses of the heads or supports, and forming a pocket or cavity in the cylinder, and devices whereby 120 said section or stave may be adjusted toward and from the center of the cylinder to vary the size of the said pocket or cavity, substantially as described. 125

7. In a machine for obtaining fibers, the combination, with a rotary cylinder, of a bed or 130

concave wherein the said cylinder works, extending beneath and upward on each side of the cylinder, and comprising a principal portion, which is fixed and extends beneath the cylinder and upward on the delivery side of the machine, and a hinged portion at the entrance side of the machine, and devices for adjusting said hinged portion toward and from the cylinder, whereby provision is afforded for varying the distance between the cylinder and bed or concave at the entrance, and without moving the principal working portion of the bed or concave, substantially as described.

8. In a machine for obtaining fibers, the combination, with a bed or concave approximately semicircular in form, of a cylinder which is approximately circular in form, working within the bed or concave, and bearings for said cylinder, which are movable horizontally to vary the distance between the bed or concave and cylinder at the entrance and delivery sides of the machine, substantially as described.

9. In a machine for obtaining fibers, the combination of a bed or concave, a cylinder working within the bed or concave, bearings or boxes for the cylinder, which are movable to vary the distance between the bed or concave and the cylinder at the entrance and delivery sides of the machine, a shaft geared to the cylinder and serving to impart motion thereto, and

bearings or boxes for said shaft, which are movable, whereby provision is afforded for adjusting said shaft correspondingly to the cylinder, substantially as described.

10. The combination of the bed or concave A, the cylinder, the bearings D, supported by the frame of the machine, and provided with the slotted arms D², and bolts g⁵, passing through the slotted arms, for securing said boxes in different positions on the frame of the machine, substantially as described.

11. The combination, with the bed or concave A, the cylinder, and the frame B, of the boxes D, provided with the lateral extensions D¹ and with the arms D², the bolts g¹, having a slotted connection with the frame, the springs g³, applied to said bolts, the screws g⁴, for limiting the downward movement of said boxes, and the bolts g⁵, all substantially as described.

12. The combination of the frame B, the bed or concave A, the cylinder, the boxes D, movable as described, the shaft F', and wheels F E, connecting it with the cylinder, and the eccentric-boxes h, fitted to the frame B, and adapted to be turned therein, substantially as described.
